UNITED STATES PATENT OFFICE.

ARTHUR O. HIGINBOTHAM, OF DENVER, COLORADO, ASSIGNOR OF ONE-HALF TO
WILLIAM A. WEIGELE, OF DENVER, COLORADO.

APPARATUS FOR SUPPLYING OXYGEN TO COMBUSTION CHAMBERS.

Application filed August 15, 1924. Serial No. 732,323.

My invention relates to an improved means for the controlled supply of oxygen to the fire bed of a boiler after firing whereby to prevent the formation of excessive smoke by a substantially complete combustion of the gases emanated from the ignited fuel and it is an object of the invention to provide a highly efficient though simple mechanism that is actuated by movement 5 of a constituent element of the furnace to admit oxygen to the fire chamber of the same at a predetermined rate and during a given period of time.

A further object is to include in said mechanism, readily adjusted means for regulating the rate at which the oxygen is admitted, and the quantity of oxygen supplied in the predetermined space of time, and another aim of the invention resides in carrying the above 10 objects into effect by a cam-operated damper-element and a time-controlled operating mechanism of novel form and arrangement, co-operatively combined, as will fully appear in the course of the following description.

The element of the furnace which by its movement actuates the time-controlled operating mechanism included in the invention, is ordinarily the door which normally closes 15 the feed-opening of the fire chamber, and it is in this connection that my invention has been illustrated in the accompanying drawings and will hereinafter be described.

It is to be understood, however, that other 20 moving constituent parts of a boiler or furnace, as for example, the reciprocating piston-ram of a mechanical push-stoker, may be employed for the same purpose without material changes in the construction and 25 arrangement of the elements comprised in the invention and well within the scope of the invention as defined in the hereunto appended claims and it will further appear that the construction of said elements is 30 specifically of a nature which permits of the time mechanism which operates the cam of the damper-element, being actuated by hand in the event of its being impractical or inconvenient to associate the mechanism 35 with a movable part of the boiler or furnace, of the character hereinbefore referred to.

A preferred embodiment of the invention

has been illustrated in the accompanying drawings in the several views of which like parts are similarly designated, and in which 55

Figure 1 represents a front view of a portion of a furnace wall and a door closing the fire-opening thereof, with the elements and parts comprised in the present invention in their operative position with relation 60 thereto, the casing enclosing the time-element of the mechanism having been shown in vertical section;

Figure 2, an enlarged sectional elevation of the adjustable governor-member of the 65 time-element which determines the duration of its operation after each actuation by movement of the fire-door;

Figure 3, a sectional detail of the adjustable anti-friction wheel which transmits 70 the movement of the cam-element of the invention to the dampers which control the admission of oxygen to the fire box;

Figure 4, an enlarged face-view of the 75 cam-element;

Figure 5 shows on a larger scale, the connections between the dampers which in the form of the invention illustrated in the drawings constitute the controlling means hereinbefore referred to;

Figure 6 represents an enlarged fragmentary vertical section along the line 6—6, Figure 1, with the fire-door in a partially open position;

Figure 7, a similar view with the door in 85 the closed position;

Figure 8 is a fragmentary vertical section taken on the line 8—8, Figure 1, and drawn to an enlarged scale;

Figure 9 is a section in the plane indicated 90 by the line 9—9 in Figure 1;

Figure 10 is an end view of the door with the dampers in the closed position, looking in the direction of the arrow A in Figure 1; and

Figure 11, a similar view showing the dampers in a partially closed position.

Referring more specifically to the drawings, 5 designates the wall of a boiler or furnace having a fire-opening 6 and a door 100 7 hinged at 8, which normally closes the same.

The door comprises a frame provided with an outwardly projecting flange 9 which de-

fines a substantially rectangular opening through which in the operation of my invention, air is admitted to the fire in the combustion chamber of the boiler.

5 The air-opening is normally closed by two lapping dampers 10 hung for pivotal movement about horizontal axes through the medium of shafts 12 extending through alined openings in the vertical portions of the flange, and the door is provided with the usual handle 13 to facilitate its movement.

10 The opening may be covered at the inside of the door by a preheating and diffusing element consisting of a series of baffle-plates 14 which are fastened in spaced relation to each other by bolts 15 passing through lugs on the door.

15 The baffle plates are angular in cross-section to form downwardly slanting apron-members 16 which cover the spaces between them; they are provided with spacing-lugs 17 on their horizontal portions through which the bolts pass; they may be curved in their horizontal planes for the diffusion 20 of the air passing through the opening and perforated to dispel the heat to which they are subjected and to lighten the construction of the door.

25 The dampers are automatically opened and closed after each movement of the door for replenishment of the fuel on the grate in the combustion chamber of the furnace, by a time-mechanism of the escapement type indicated in its entirety by the reference 30 character 19.

30 The time-movement includes a gear-train 20, and an escapement 21 mounted to oscillate about a vertical axis, and it is enclosed in a dust-proof casing 22 fastened upon a 35 side of the door flange by bolts 23.

35 A lever 24 supported for oscillation about the spindle of the driving wheel 25 of the time-movement, projecting exteriorly of the casing, carries a pivoted pawl 26 which normally engages with a notched wheel 27 at the end of the spindle and lugs 28 and 29 on the casing limit the arcuate movement of the lever.

40 The time-mechanism is operated by a coiled spring 30 disposed between a shoulder 31 on the lever 24 and a thereto opposed shoulder 32 on a bell crank 33 which is mounted to rock in bearings at the lower portion of the door by means of a shaft 45, and a rod 35 fastened to the lever and moving loosely through an opening in the shoulder of the bell crank, passes through the spring to prevent its lateral deflection.

45 A pin 36 on the arm of the bell crank opposite to that engaged by the spring, passes loosely through an opening in the door to engage the frame of the boiler around the fire opening when the door is in the closed position.

50 The escapement hereinbefore referred to

carries at the upper end of its vertical shaft 37 two weights 38 which by their distance from the axis of oscillation, regulates the velocity of the movement of the time mechanism imparted thereto by expansion of the 55 spring as will hereinafter be more fully explained.

55 The weights are mounted upon a transverse rod 39 mounted to rotate on a forked head 40 at the end of the shaft 37.

60 The rod has right-hand and left-hand screw threads cooperating with corresponding screw-threads in bores of the weights and it is provided with a knurled enlargement 41 between the members of the forked head to facilitate its rotation.

65 A second rod 42 fixed on the head and passing freely through plane bores of the weights parallel to their threaded bores, 70 guide the weights and hold them against rotation with the screw-shaft.

75 The time mechanism when actuated by expansion of the spring, effects the rotary movement of a shaft 43 which is mounted for rotation in alined openings of the upright portions of the door flange and which at the side of the flange opposite to that at which the time-mechanism is disposed, carries a cam-element 44 which constitutes the instrumentation by which the dampers of the 80 door are opened and closed when the mechanism is in operation.

85 The cam-element in its simplest form, consists of a disk having a peripheral, preferably grooved edge of irregular form. The 90 edge of the cam is engaged by an anti-friction wheel 45 on the wrist-rod 46 of a crank 47 at the adjacent end of the shaft of the upper damper and a bar 48 connecting said rod with the wrist of a parallel crank 49 on the shaft of the lower damper provides for the conjunctive movement of the dampers through the instrumentation of the cam.

95 It is preferred to compose the cam-element of a number of steps of corresponding outlines but progressively decreasing diameters to vary the extent to which the dampers are 100 opened by the operation of the time-mechanism, and the anti-friction wheel 45 is slidably mounted on the wrist-rod 46 to permit 105 of its being adjusted from one step of the cam element to another across the entire width thereof.

110 Having thus described the construction and co-operative arrangement of the component elements of my invention, its operation is as follows:

115 When the fire-door is in its normal closed position and the time-mechanism is at rest, the dampers close the opening defined by 120 the flange of the door, as shown in Figures 1 and 10.

125 The anti-friction wheel of the dampers is placed in one of the grooved steps of the cam-element according to the extent to which 130

the dampers are to be opened and the pawl 26 on the lever 24 is disposed to engage in one of the notches of the wheel 27 on the shaft of the driving wheel of the clock-mechanism as shown in Figures 6 and 7.

When the fire-door is opened for the purpose of supplying the fire in the combustion chamber of the furnace with fresh fuel, the pin 36 on the bell crank 33 is projected through the opening of the door by gravity of the parts as shown in Figure 6, it being understood that the opening through which the pin passes is sufficiently wide to permit of the slight lateral displacement of the pin caused by the arcuate movement of the end of the bell crank-arm with which it is connected.

When after the fire has been coaled, the door is returned to its closed position, the pin by contact with the furnace wall, compels the bell crank to move about its axis and the corresponding movement of the shoulder 32 compresses the spring against the opposed shoulder of the lever 24 which is held through the medium of the pawl 26; by the frictional resistance of the time-mechanism of which it is a part.

The bell crank in the position to which it is adjusted by the closing movement of the door, has its arm engaged by the spring 30, at so small an angle to a perpendicular passing through the axis of the shaft 34, that the compressed spring will exert the pressure resulting from its expansion, practically completely upon the lever 24 of the time-mechanism while its tendency to open the fire-door by downward movement of the bell crank, is negligible.

The expansive movement of the spring causes the operation of the time-mechanism at a rate regulated by the position of the weights of the escapement relative to its axis of oscillation, until the lever 24 engages with the stop 29.

The escapement thus serves as a governor controlling the rate of rotation of the cam-shaft 43 which is driven by the time mechanism as hereinbefore described, and it will be apparent that by adjustment of the weights through the medium of the screw 39, the velocity of the cam-shaft may be regulated to fix the time period during which the dampers are opened and closed according to variable circumstances such as the kind of fuel supplied to the furnace and the quantity of fuel fed into the furnace at one time.

The rotary motion of the shaft 43 is through the medium of the cam-element converted into an opening movement of the pivoted dampers at a rate dependent on the peripheral form of the cam with which the wheel of the crank-movement of the dampers is in contact.

Thus, by the rotary movement of the cam

illustrated in Figure 4, in the direction of the arrow C and at a rate regulated by the governor of the time mechanism, the dampers are gradually opened by upward movement of the wheel 43 until it engages with the periphery of the cam at its point of greatest diameter after which it is lowered under the influence of its own weight and that of the other members of the cam-movement of which it is a part until the dampers are again in the closed position.

It will thus be apparent that the time period during which the dampers are open to admit oxygen to the fire chamber is regulated by the rate of motion of the time mechanism under control of its escapement governor and that the extent to which the dampers are opened and the proportionate lengths of their opening and closing movements are predetermined by the shape and size of the cam. By adjusting the contact wheel from one step of the cam to another or by interchanging the cam with another of different shape, the extent to which the doors are opened and the proportionate lengths of the gradual opening and closing movements of the dampers may be varied to any desired degree.

The air entering the combustion chamber of the furnace past the gradually opening dampers is preheated by contact with the baffle plates and diffused so as to spread evenly over the entire area of the fuel bed, and by proper regulation of the movement of the dampers in the manner hereinbefore described, the air is supplied in quantities varying according to the requirements of the fuel to form a substantially perfect combustible mixture with the gases evolved by ignition of the fuel, and thereby prevent the formation and escape of smoke.

The baffles formed and relatively arranged as shown in the drawings, also prevent the escape of heat through the opening in the door when the dampers are opened and thereby aid in saving fuel.

When it is desired to close the fire-door without actuation of the damper-operating time mechanism, the pawl 26 is disengaged from the notched wheel 27 as shown in broken lines in Figure 6 and in order to provide for an air passage below the lower damper, of equal width to that above the upper damper, the lower portion of the door-flange 9 is concaved as best shown in Figure 9.

Having thus described my invention, what I claim and desire to secure by Letters Patent is:

1. Oxidizing apparatus for furnaces comprising in combination with the combustion chamber of a furnace, a movable element, a damper controlling the admission of air to the combustion chamber, and means actuated by movement of said element to gradually open the damper and reclose the

same in movements consuming a predetermined period of time.

2. Oxidizing apparatus for furnaces comprising in combination with the combustion chamber of a furnace, a movable element, a damper controlling the admission of air to the combustion chamber, and means actuated by movement of said element to open the damper by a gradual movement consuming 10 a predetermined period of time and reclose the same.

3. Oxidizing apparatus for furnaces comprising in combination with the combustion chamber of a furnace, a damper controlling 15 admission of air to the combustion chamber, a cam, means to open the damper by movement of the cam, and mechanism for operation of the cam during a predetermined time-period.

20 4. Oxidizing apparatus for furnaces comprising in combination with the combustion chamber of a furnace, a damper controlling admission of air to the combustion chamber, a cam, means for the operation of the 25 damper by movement of the cam, and time-mechanism for operation of the cam.

5. Oxidizing apparatus for furnaces comprising in combination with the combustion chamber of a furnace, a movable constituent 30 element of the furnace, a damper controlling admission of air to the combustion chamber, and time-mechanism to gradually open the damper, actuated by movement of said element.

35 6. Oxidizing apparatus for furnaces comprising a fire-door having an opening, a damper closing the opening, a cam for the operation of the damper, and time-mechanism for operation of the cam, actuated by 40 movement of the door.

7. Oxidizing apparatus for a furnace having an opening to its combustion chamber, a damper closing the opening, a cam for the operation of the damper, a fire door, and time-mechanism for operation of the cam, actuated by 45 movement of the door.

8. Oxidizing apparatus for furnaces comprising in combination with the combustion chamber of a furnace, a damper controlling 50 admission of air to the combustion chamber, a time-mechanism, means for the actuation of the time-mechanism including a spring compressible by linear stress, and means to effect the operation of the mechanism by 55 expansion of the spring, and an element driven by the time-mechanism to open the damper.

9. In oxidizing apparatus for furnaces, a time-mechanism, a compressible spring, a 60 member adapted to compress the spring by contact with a relatively stationary abutment, and means to effect the operation of the mechanism by expansion of the spring.

10. Oxidizing apparatus for furnaces, 65 comprising in combination with the combus-

tion-chamber of a furnace, a damper controlling admission of air to the combustion chamber, a time-mechanism, a lever, a pivoted pawl on the lever, in operative engagement with a member of the mechanism, 70 a crank, a compressible spring between opposed shoulders on the lever and the crank, and an element driven by the time-mechanism to open the damper.

11. In oxidizing apparatus for furnaces, 75 a time-mechanism, a lever, a pivoted pawl on the lever, in operative engagement with a member of the mechanism, a crank adapted to be moved by contact with a relatively stationary abutment, and a compressible spring between opposed shoulders on the lever and the crank. 80

12. Oxidizing apparatus for furnaces, comprising in combination with the combustion-chamber of a furnace, a damper controlling admission of air to the combustion chamber, a time mechanism, means for the actuation of the time-mechanism including a lengthwise compressible, coiled spring, a member to compress the spring, and means 85 to effect the operation of the mechanism by expansion of the spring, and an element driven by the time-mechanism to open the damper. 90

13. Oxidizing apparatus for furnaces, 95 comprising in combination with the combustion chamber of a furnace, a damper controlling admission of air to the combustion chamber, time-mechanism for the operation of the damper, including an adjustable 100 governor which regulates its rate of motion, and means for actuation of the time-mechanism.

14. Oxidizing apparatus for furnaces, comprising in combination with the combustion chamber of a furnace, a damper controlling admission of air to the combustion chamber, time-mechanism for the operation of the damper, an escapement included in the mechanism, comprising an oscillating 105 shaft and a weight carried by the shaft adjustably to vary its distance from the axis of oscillation, and means for actuation of the time-mechanism. 110

15. Oxidizing apparatus for furnaces, 115 comprising in combination with the combustion chamber of a furnace, a damper controlling admission of air to the combustion chamber, time-mechanism for the operation of the damper, an escapement included 120 in the mechanism, comprising an oscillating shaft, weights carried by the shaft, and a rotary screw element for adjustment of the weights to simultaneously vary their distance from the axis of oscillation, and means 125 for actuation of the time-mechanism.

16. Oxidizing apparatus for furnaces comprising in combination with the combustion chamber of a furnace, a damper controlling the admission of air to the combus- 130

tion chamber above the fire, and a time-
mechanism to gradually open the damper
and reclose the same in movements consum-
ing a predetermined period of time.

17. Oxidizing apparatus for furnaces
comprising in combination with the combus-
tion chamber of a furnace, a damper con-
trolling the admission of air to the combus-
tion chamber above the fire, and a time-
mechanism to gradually open the damper
by a gradual movement consuming a prede-

termined period of time and reclose the
same.

18. Oxidizing apparatus for a furnace
having a door and a damper, comprising a ¹⁵
cam for the operation of the damper, and
time mechanism for operation of the cam,
actuated by movement of the door.

In testimony whereof I have affixed my
signature.

ARTHUR O. HIGINBOTHAM.
